COMBINED LOCK AND SEAL DEVICE

Nicholas A. Welch, West Hartford, Conn., assignor to The American Hardware Corporation, New Britain, Conn., a corporation of Connecticut

Application November 3, 1950, Serial No. 193,817

11 Claims. (Cl. 70—50)

1

This invention relates to a combined lock and seal device and more particularly to a lock having means permitting the sealing thereof, with a replaceable sealing member, so as to prevent operation of the lock by unauthorized persons.

It is an object of my invention to provide novel means to permit the sealing of a lock having a key operated plug in such a manner that the said plug may not be operated without first removing or destroying the sealing member and thereby providing an indication that the lock has been tampered with.

A further object of my invention is to provide sealing means which are particularly adapted for padlocks, and which are highly efficient in the operation thereof and may be incorporated in a padlock in a very inexpensive manner.

Further objects and advantages of this invention will be more clearly understood from the following description and the accompanying drawings in which:

Fig. 1 is a front view of a padlock which contains my improved sealing means.

Fig. 2 is a similar view, with parts thereof shown in section, illustrating the construction of the lock and sealing means.

Fig. 3 is an end view of said lock, partly in section, on line 3—3 of Fig. 2.

Fig. 4 is a front view, partly in section, illustrating my improved sealing means when incorporated in a padlock having a master sleeve.

Fig. 5 is a bottom view thereof, partly in section, on line 5—5 of Fig. 4.

Fig. 6 is a front view of the padlock case showing a modified form of slot formation therein.

Fig. 7 is a plan view of a key plug illustrating a modified form of slot formation therein.

Fig. 8 is a side view of said key plug.

Fig. 9 is a front view of a padlock case illustrating the use of a round hole therethrough in lieu of the slot.

Fig. 10 is an elevational view of a key which may be used in conjunction with the form of the padlock illustrated in Fig. 9.

In the embodiment of my invention illustrated in the drawings, the numeral 5 denotes the case of a padlock in which a shackle member 6 is moveable to locked and unlocked positions; the said shackle member being retained in locked position in said case by means of a conventional locking bolt, not shown, which is commonly controlled by a key operated plug 7 that is rotatable within the case by means of a key intended for said mechanism and adapted to operate a series of tumblers 8 in order to release the said plug and permit rotation thereof by the key.

My present invention is particularly directed to the provision of means whereby the said lock may be sealed with a frangible sealing member to prevent operation of the key operated mecha-

2

nism, particularly when the shackle member is in its locked condition so that it cannot be operated to its unlocked position without the sealing member first having been removed or damaged and thereby giving indication that the lock has been tampered with by an unauthorized person.

Such sealing means preferably comprise a slot 9, or other suitable opening, which extends through the case 5 and across the opening 10 therein which contains the plug 7, and a slot 11 which extends through the said plug and is in alignment with the slot 9 so as to provide an opening extending entirely through the case and plug, as illustrated in Fig. 3, which will receive a ribbon-like frangible sealing member 12.

When the lock is thus sealed, the sealing member will connect the plug to the case so that it cannot be rotated with the key or any other member, without breaking or greatly damaging the sealing member and thereby providing an indication of tampering. Moreover, the said sealing member will extend across the conventional key slot 13 in said plug and prevent insertion of the key thereinto so that the plug may not be operated while the lock is in sealed condition.

If desired, in order to facilitate the manufacture and thereby reduce the cost of producing this sealing means, the case and plug may be constructed as shown in Figs. 6 to 8 wherein a notch 9-a is cut across the bottom portion of the case, to take the place of the slot 9, and the slot 11-a in the plug is formed with a T formation to permit the cutting of said slot with a milling operation.

In the formation illustrated in Figs. 4 and 5, the lock includes a master sleeve 14, and this sleeve is also provided with a slot 15 which extends through the sleeve and is in alignment with the slots 9 and 11 through the case and key plug so that a frangible seal inserted through the slots in this type of a lock will seal the master sleeve, in addition to the plug, against operation.

It will be understood that, if desired, round holes may be used instead of the above described slots, as shown at 16 in Fig. 9, to further reduce the cost of manufacture and a frangible wire sealing member may be used instead of the ribbon-like member 12.

When a padlock is employed to lock cases or cabinets containing emergency equipment, such as fire-fighting apparatus and the like, it is necessary that the lock be easily and quickly operated in case of necessity. It is still desirable, however, to seal such locking means in order to prevent tampering with the equipment which might render it inoperable in an emergency.

Heretofore, padlocks having frangible shackles have been used to lock such cabinets or cases, and in such padlocks it has been necessary to break

the shackle in order to obtain access to the equipment. This is objectionable in view of the fact that the entire lock must be replaced once the shackle has been broken.

The form of my improved padlock and seal illustrated in Fig. 9 is particularly suited for the above described purpose and, when so used, the operating key 17 illustrated in Fig. 10, is provided with a hole 18 therethrough which, when the key is in operating position in the lock plug, is aligned with the hole 16. A frangible wire seal may then be passed through the openings 16 and 18 thus sealing the key in the lock plug and also preventing rotation of the plug, but still permitting immediate operation of the key when the seal is broken in case of an emergency. With this arrangement, the operating key is always readily accessible and can not become lost. Furthermore, if the seal is broken in the absence of an emergency, an indication will be given that the apparatus has been tampered with.

It will be understood that the key may be provided with a slot instead of the opening 18 and used with other forms of the lock as illustrated.

I claim:

1. A lock adapted for use as a seal device including a lock body having aligned openings therein, and a key-operated mechanism in said body including a rotatable key plug having an opening extending therethrough which is alignable with the openings in said body; said openings being adapted to receive a sealing member for preventing operation of said rotatable key plug.

2. A lock adapted for use as a seal device comprising a lock case having an opening therethrough, and a key-operated mechanism in said case including a movable member having a key slot and an opening extending therethrough in communication with said key slot; the said openings being alignable to receive a sealing member for preventing the insertion of a key into said key slot.

3. A lock adapted for use as a seal device comprising a lock case having an opening therethrough, and a key-operated mechanism in said case including a rotatable plug having a key slot therein and an opening extending therethrough in communication with said key slot; the said openings being alignable to receive a sealing member for preventing rotation of the said key plug and insertion of a key into the said key slot.

4. A lock adapted for use as a seal device including a lock case having an opening therethrough, and a key-operated mechanism in said case including a rotatable key plug and a rotatable master sleeve surrounding said key plug; the said case, plug and master sleeve having aligned openings extending therethrough to receive a sealing member for preventing operation of said mechanism.

5. A lock adapted for use as a seal device comprising a lock case, and a key-operated mechanism within said case including a rotatable plug having a key slot therein and a rotatable sleeve surrounding said plug; the said plug having an opening therethrough in communication with the key slot and alignable with openings extending through the case and rotatable sleeve to thereby provide an opening through the lock to receive a sealing member for preventing the insertion of a key into the key slot.

6. A lock adapted for use as a seal device comprising a lock case having a notch therein, and

4
a key-operated mechanism in said case including a rotatable plug; the said plug having a slot therein which is alignable with the notch to provide an opening extending through said lock for the reception of a sealing member to prevent the operation of said mechanism.

7. A lock adapted for use as a seal device comprising a case having an opening extending therethrough, and a key-operated mechanism in said case including a rotatable plug; said plug having a T-slot extending through a portion thereof and in alignment with the opening extending through the lock for the reception of a sealing member to prevent the operation of said mechanism.

8. A lock adapted for use as a seal device comprising a case having an opening therethrough, and a key-operated mechanism within said case including a rotatable plug having a key slot therein; a portion of said plug being provided with a T-slot which extends thereacross in communication with said key slot and is alignable with the opening in the case to thereby provide an opening extending through said lock for the reception of a frangible sealing member to prevent insertion of a key into the key slot.

9. A combined lock and key adapted for use as a seal device comprising a lock case having an opening therethrough, a lock mechanism in said case including a rotatable member having an opening extending therethrough in alignment with the opening in said case, and a key extending into said rotatable member for operating said member; the said key having an opening therethrough in alignment with the openings in the case and rotatable member to thereby provide an opening extending through the lock to receive a frangible seal for preventing rotation of the rotatable member and removal of the key from said member.

10. A lock adapted for use as a seal device including a lock body having an opening therein, and a key-operated mechanism in said body including a rotatable key plug having an opening therein that is alignable with the opening in said body; said openings being adapted to receive a sealing member for preventing operation of said key plug.

11. A combined lock and key adapted for use as a seal device comprising a lock case having an opening therethrough, a lock mechanism in said case including a rotatable member having an opening extending therethrough in alignment with the opening in said case, and a key extending into said rotatable member for operating said member and having an opening therethrough; the openings in said case and rotatable member and said key being adapted to receive a seal member for preventing rotation of the rotatable member and removal of the key therefrom.

NICHOLAS A. WELCH.
